UNITED STATES PATENT OFFICE.

FRANK WILLIAM PETERSON, OF PEORIA, ILLINOIS.

ELECTRIC INCANDESCENT LAMP.

1,341,581.

Specification of Letters Patent. Patented May 25, 1920.

Application filed February 4, 1919. Serial No. 274,835.

To all whom it may concern:

Be it known that I, FRANK WILLIAM PETERSON, a citizen of the United States, residing at Peoria, State of Illinois, have invented new and useful Improvements in Electric Incandescent Lamps, of which the following is a specification.

This invention has reference to improvements in electric incandescent lamps, and the principal object of the invention is to provide means for renewing the filament-carrying member when the original filament has been destroyed or for replacing said member by a similar member carrying filaments for giving a light of a different candle power. Another object of the invention is to provide the glass bulb with a screw-threaded end for receiving a metal cap, which is adapted to fit in the ordinary receiving socket.

Another object is to provide a vacuum globe in which the filament is placed and which is provided with a receiving means with which engages a pair of supporting wires secured to the cap and acting as conductors for the current.

The invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:

Figure 1 is a sectional view of the invention.

Fig. 2 is a view of the cap.

Fig. 3 is a detailed view.

In these views, 1 indicates a glass bulb of the usual form but provided with a screw-threaded cylindrical end 2, which is open. This end is adapted to be closed by a screw-threaded cap 3, which is so formed as to fit the ordinary electric light socket. This cap

is made of any suitable material and is provided with the usual contacts. This cap has 50 secured to its interior a pair of depending strips 4, which are of sufficient strength to support the filament-carrying bulb 5. This bulb is made of glass and contains the filament 6. The air is exhausted from this bulb 55 in the usual manner. The end of this bulb carries a pair of contact posts 7, having their inner ends connected with the filament and these posts receive the free ends of the strips 4. The filament-carrying globe 5 is 60 made small enough to pass within the neck or cylindrical part 2 of the main bulb, and is supported in said bulb by the strips 4. These strips 4 also act as conductors for the current. It will be understood that a 65 vacuum must be formed in the globe or bulb 5 but it is not necessary to have a vacuum in the outer bulb.

It will thus be seen that when the filament 6 is burnt out or otherwise destroyed, the 70 bulb 5 can easily be removed and replaced by a new one or said bulb may be replaced by a similar bulb to provide light of a different candle power.

What I claim is:

1. An electric lamp of the class described, comprising a vacuum globe having a filament therein, an outer globe for containing the vacuum globe, said outer globe having a screw-threaded neck, a screw-threaded socket 80 engaging cap engaging said neck and a pair of conductor strips connecting the cap with the vacuum globe. 75

2. An electric lamp of the class described comprising an outer globe shaped like an 85 ordinary electric bulb, a cap removably attached to the neck of said globe and provided with screw threads to engage an electric light socket, a pair of conductor strips carried by the cap and extending into the 90 globe, a vacuum globe in said outer globe and means for detachably connecting the terminals of said vacuum globe to said strips.

In testimony whereof I affix my signature. 95

FRANK WILLIAM PETERSON.
